UNITED STATES PATENT OFFICE.

WILLIAM W. DOTY, OF NEW YORK, N. Y., ASSIGNOR, BY DIRECT AND MESNE ASSIGNMENTS, OF TWO-THIRDS TO CHARLES J. BICKMANN, JOSEPH C. GRAUTEN, AND CHARLES C. GRAUTEN, OF SAME PLACE.

RAILROAD-SWITCH.

SPECIFICATION forming part of Letters Patent No. 556,260, dated March 10, 1896.

Application filed June 20, 1895. Serial No. 553,424. (No model.)

To all whom it may concern:

Be it known that I, WILLIAM W. DOTY, of New York, in the county and State of New York, have invented a new and Improved 5 Railroad-Switch, of which the following is a full, clear, and exact description.

The object of the invention is to provide a new and improved railroad-switch which is simple and durable in construction, more especially designed for use on street-railways, and arranged to hold the switch normally closed to the side track, and to permit the side track to automatically open and close the said track relative to the main track.

15 The invention consists of certain parts and details and combinations of the same, as will be fully described hereinafter and then pointed out in the claims.

Reference is to be had to the accompanying 20 drawings, forming a part of this specification, in which similar characters of reference indicate corresponding parts in all the figures.

Figure 1 is a plan view of the improvement with parts in section. Fig. 2 is a sectional 25 side elevation of the same. Fig. 3 is an inverted plan view of the car for the said track. Fig. 4 is an enlarged cross-section of the improvement on the line 4 4 of Fig. 1. Fig. 5 is a like view of part of the improvement on 30 the line 5 5 of Fig. 1, and Fig. 6 is a similar view of the same with the parts in a different position.

The main track A A' is provided in the rail A with a switch-point B, adapted to open and 35 close the main track at the side of the track-rail C. The point B is pivoted at B', and its free end is formed on the under side with a recess B², (see Figs. 5 and 6,) in which projects the upper end of an L-shaped arm D, 40 loosely connected by a set-screw E with the forward end of a lever F, fulcrumed at F' in a suitable casing G, arranged at the outside of the main track, as plainly indicated in the drawings.

45 The rear end of the lever F is provided with a bracket F², on which is secured an obliquely-extending arm F³, adapted to be actuated by a mechanism on the car I, so as to impart a swinging motion to the lever F to move the 50 switch-point B into an open position to per-

mit the car to actuate the lever F and pass from the main track A A' upon the rails C and C' of the said track.

In order to impart a proper swinging motion to the lever F, I provide the latter on 55 the bracket F² with a projection F⁴, adapted to abut against a bracket H, secured to a sleeper A² for the rail A, as plainly indicated in Fig. 4. This projection F⁴ serves as a second fulcrum for the lever F to move the forward end of the lever inward at the time the arm F³ is pressed inward by the mechanism on the car I. This mechanism on the car I is provided with double arms J, secured on 60 the ends of a shaft K, extending transversely 65 and journaled in suitable bearings attached to the under side of the car I.

On the shaft K, at or near the middle thereof, is secured a double arm K', connected by links K² with levers L L' extending in opposite directions and fulcrumed on the under side of the car, the outer ends of the levers reaching to the two platforms at the ends of the car I.

The outer end of each lever is provided with 75 an upwardly-extending rod N, formed on its top with a disk adapted to be pressed on by the foot of the operator standing on the platform, so that a swinging motion is given to the respective lever L or L' to turn the shaft 80 K and to throw the rear end of the double-armed lever downward, so as to engage the arm F³. As the latter stands obliquely to the track A, the arm J in striking the arm F³ presses the latter inward to move the projection F⁴ in engagement with the bracket H, so 85 that the lever F is turned to swing with its forward end inwardly to cause the loosely-connected arm D to push the switch-point B 90 inwardly into the position shown in Fig. 5—that is, into an open position—to permit the car to pass from the main track A A' upon the side-track rails C C'.

In order to hold the lever F in an innermost position, I provide the forward end of 95 the said lever with a block F⁵, adapted to slide over a transverse beam G' forming part of the casing G. On the beam G' is formed a shoulder or drop G², adapted to be engaged by the block F⁵, so that when the lever swings 100

inwardly at its forward end the said block F⁵ drops behind the shoulder G² to lock the lever in this innermost position and consequently hold the switch-point B open. The 5 car now passes upon the side-track rails C C', and when the rear wheels have passed upon the side-track rails then one of the forward wheels comes in contact with the projecting end O³ of a lever O, fulcrumed at O² in the 10 casing G, and engaging with its rear end O' the under side of the block F⁵ to lift the latter with this end of the lever F upward, to bring the block over the shoulder G² and to permit a spring P, pressing on the said lever F, to return the latter to its forward normal position. The lever F in returning to this 15 position carries the arm D of the switch-point B back to its original position—that is, again closing the switch to the side track.

20 It is understood that the pivot for the lever F is sufficiently loose to permit the projection F⁴ to act as a fulcrum for the lever F to swing the forward end thereof inward when the arm F³ is pressed by the rear end of the double 25 arm J. When the block F⁵ is lifted by the lever O, as previously described, to disengage the shoulder G², the lever swings back to its normal position by the action of the spring P, the said lever swinging on the fulcrum F⁴.

30 It will further be seen that when the switch-point B is in a normal closed position a vehicle passing over the switch will accidentally shift the point into an open position; but as soon as the vehicle-wheel has left the 35 switch the latter will swing back to its closed position by the action of the lever F as the latter is pressed by the spring P, and only yields sufficiently at the time the wheel of the vehicle comes in contact between the rail C' 40 and the switch-point.

The device is very simple and durable in construction, is not liable to get out of order, and can be readily attended to, as the casing G and the parts contained therein are all located on the outside of the track.

45 It will further be seen that the mechanism on the car for manipulating the lever F is very simple, and the said mechanism may be actuated from either end of the car without changing any of the parts.

Having thus fully described my invention, I claim as new and desire to secure by Letters Patent—

50 1. A railroad-switch, provided with a lever pressed on by a spring and connected at its forward end with the switch-point, the said

lever having two fulcrums and being adapted to be actuated by a device upon the car, substantially as shown and described.

2. A railroad-switch, comprising a spring- 60 pressed lever, an arm extending in an oblique direction relative to the track, the said arm being held on a bracket of the lever to be pressed on by a device on the car, the forward end of the said lever being provided with a 65 block adapted to engage a shoulder to lock the lever in position, substantially as shown and described.

3. A railroad-switch, comprising a spring- 70 pressed lever, an arm extending in an oblique direction relative to the track, the said arm being held on a bracket of the lever to be pressed on by a device on the car, the forward end of the said lever being provided with a 75 block adapted to engage a shoulder, to lock the lever in position, and a second lever adapted to engage the said block, to lift the latter over the shoulder, the said second lever extending into the side track, to be engaged by one of the car-wheels as the latter pass upon the side 80 track, substantially as shown and described.

4. In a switch, the combination with the switch-point, of an operating-lever, the same having two fulcrums, substantially as described. 85

5. In a switch, the combination with the switch-point, of an operating-lever, the same comprising a horizontal portion and a perpendicular portion at one end, and a fulcrum for each portion, substantially as described. 90

6. In a switch, the combination with the switch-point, of an operating-lever connected thereto, a beam having a shoulder thereon and over which beam one end of the lever moves, and a second lever having a bent end 95 movable through an opening in the beam and capable of lifting the operating-lever past the shoulder on said beam, substantially as described.

7. In a switch, the combination with the switch-point and a casing, of an operating-lever fulcrumed therein and having a perpendicular portion at one end, a bracket rigid with the casing and forming the fulcrum of said perpendicular portion, and a fulcrum for 100 the main part of the operating-lever, the said lever being connected to the switch-point, substantially as described.
